(57) **CLAIM**

The ornamental design for a display screen or portion thereof with animated icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with animated icon showing a first image of the claimed design;

FIG. 2 is a second image thereof;

FIG. 3 is a third image thereof;

FIG. 4 is a front view of a second embodiment of a display screen or portion thereof with animated icon showing a first image of the claimed design;

FIG. 5 is a second image thereof;

FIG. 6 is a third image thereof;

FIG. 7 is a front view of a third embodiment of a display screen or portion thereof with animated icon showing a first image of the claimed design;

FIG. 8 is a second image thereof;

FIG. 9 is a third image thereof;

FIG. 10 is a front view of a fourth embodiment of a display screen or portion thereof with animated icon showing a first image of the claimed design;

FIG. 11 is a second image thereof; and,

FIG. 12 is a third image thereof.

The broken lines in the figures show a display screen or portion thereof, and form no part of the claimed design.

The appearance of the animated image sequentially transitions between the images shown in FIGS. 1-3, 4-6, 7-9, and 10-12. The process or period in which one image transitions to another forms no part of the claimed design.
